JAMES T. KING, OF TORONTO, ONTARIO, CANADA.

MOUTHPIECE FOR BRASS WIND INSTRUMENTS.

1,410,322.

Specification of Letters Patent. Patented Mar. 21, 1922.

Application filed January 11, 1918. Serial No. 211,354.

(GRANTED UNDER THE PROVISIONS OF THE ACT OF MARCH 3, 1921, 41 STAT. L., 1313.)

To all whom it may concern:

Be it known that I, JAMES T. KING, of the city of Toronto, in the county of York, Province of Ontario, Canada, a subject of the King of Great Britain, have invented certain new and useful Improvements in Mouthpieces for Brass Wind Instruments, of which the following is a specification.

This invention relates to mouth pieces such as are employed with cornets, trumpets, horns and the like. In such mouth pieces a rim against which the player presses his lips surrounds a cup-shaped cavity, which merges more or less gradually or abruptly as the case may be with the bore of the mouthpiece.

It is well known that the quality of the tone produced by the use of a mouthpiece depends on the shape and proportions of the cup and the character of the throat where the cup merges into the bore, and my object is to devise a form of mouthpiece which, with necessary modifications, is applicable for use in the mouthpieces of cup form of the brass instruments employed in bands and orchestras to enable the performer to secure with ease certain tone characteristics not ordinarily, or in some cases, not easily obtainable with ordinary mouthpieces. In the case of the euphonium these desirable characteristics may be briefly set forth as follows:—

1. The tone all through should be round, flutey and pervading.
2. In the upper register, the tone should be clear and full, not shrill or brassy.
3. In the lower register, the tone should be mellow, rich and with great solidity or body.
4. These qualities I obtain by means of the special form of the cup of the mouthpiece hereinafter particularly described and illustrated in the accompanying drawings in which—
5. Fig. 1 is an end view of my improved mouthpiece;

Fig. 2 a longitudinal section of the same;

Fig. 3 an elevation of the same; and

Fig. 4 a longitudinal section of a slight modification.

In the drawings like numerals of reference indicate corresponding parts in the different figures.

The main elements of the mouthpiece

which is integrally made and of fixed form 55 and dimensions are the rim 1, the cup 2, the throat 3 and the bore 4.

The rim 1 may be of any ordinary form and size as far as its external parts are concerned. The cup 2, however, departs entirely from known forms inasmuch as it is given a diameter immediately below the rim 60 somewhat greater than the opening at the rim so as to produce an enlargement of the cup adjacent the rim.

This enlargement is preferably produced by giving the longitudinal sectional contours of the inner surfaces of the rim, cup and throat the form shown in the drawings. It will be noted that the inner surface of 70 the rim is convexly curved, the convex curve merging into the concave curve of the enlargement of the cup and this concave curve merging in turn into the convex curve of the throat. The longitudinal section 75 curve referred to is thus a double ogee, as the direction of the curve changes twice in its length.

Preferably the difference between the greatest diameter of the cup and the least diameter of the opening at the rim will be less than the distance between the point of least diameter of said opening and the point at which the diameter of the interior of the cup again becomes the same as the least 85 diameter of the opening at the rim.

While the form shown in Fig. 2 is my preferred construction, particularly for the euphonium, the shape of the mouthpiece may be widely varied without departing 90 from the spirit of my invention as long as an enlargement of the cup below the rim with curved outlines is retained. The cup, for instance, may be concave adjacent the throat and the bore and throat meet at an 95 angle as shown in Fig. 4. To those skilled in the art, other slight changes will be obvious which may be made to suit the mouthpiece to different instruments or to attain desired characteristics in tone production.

What I claim as my invention is:—

1. A mouthpiece for brass wind instruments, in which a cup provided with a rim integral therewith communicates with a suitable bore, having the interior of the cup just below the rim of greater diameter than the opening at the rim, the longitudinal

sectional contours of the interior of the cup from the rim to the throat being without angles.

2. A mouthpiece for brass wind instru-

5 ments, in which a cup provided with a rim integral therewith communicates with a suitable bore, having the longitudinal sec-
10 tional contours of the inner surfaces of the rim and the cup adjacent the lip of an ogee shape to form a convex inner edge to the rim and a concave enlargement of the cup below the rim.

3. A mouthpiece for brass wind instru-
15 ments, in which a cup provided with a rim integral therewith communicates with a suitable bore, having the longitudinal sec-
30 tional contours of the inner surface of the

cup of an ogee shape to form a concave enlargement of the cup below the rim merging into a convex throat where the cup joins 20 the bore.

4. A mouthpiece for brass wind instru-
25 ments, in which a cup provided with a rim integral therewith communicates with a suitable bore, having the longitudinal sec-
30 tional contours of the inner surfaces of the rim and cup of a double ogee shape to form a convex inner edge to the rim and a concave enlargement of the cup below the rim merging into a convex throat where the cup joins the bore.

Signed at Toronto, Canada, this 31st day of Dec. 1917.

JAMES T. KING.
